UNITED STATES PATENT OFFICE

2,539,729

PAINT AND ENAMEL MILL

Jack Cufflin, Verdun, Quebec, Canada

Application June 28, 1948, Serial No. 35,731

2 Claims. (Cl. 241—67)

1

The invention relates to improvements in a paint and enamel mill, as described in the present specification and illustrated in the accompanying drawings that form a part of the same.

The invention consists essentially of the novel features of construction as pointed out broadly and specifically in the claims for novelty following a description containing an explanation in detail of an acceptable form of the invention.

The objects of the invention are to devise a means for the dispersion of particulate groups of solids, which are already of extreme fineness, in various vehicles to provide a paint and enamel mill having as components a roll and a roll contacting flexible belt, between which the material passes to be milled thereby, the components adapting an increased milling area to be provided and maximum milling to be effected on one passing of the material between the same; to furnish a dispersing device which will break-up finely ground particles in a paste thus thoroughly mixing the same; to assure the proper mixing of ingredients in paste form such as paints, chocolates and the like to make a paint and enamel mill having a roll and a roll contacting flexible belt between which the combined mix of pigments and vehicles pass and by which the group of particles is broken up and the particles themselves reduced to extreme fineness; to contrive a small dispersing device which will thoroughly break up the pigment in a vehicle in the same time or less than that of large conventional devices; to eliminate the necessity of precision like adjustment in a dispersing machine, and to render the same self-adjusting; to construct a dispersing device having few and simple parts and inexpensive to manufacture; and generally to provide a dispersing device which will be durable, dependable and efficient in its use.

In the drawings:

Figure 1 is a front view of the dispersing device.

Figure 2 is a plan view of Figure 1.

Figure 3 is an end view of the dispersing device.

Figure 4 is a cross sectional view as taken on the line 4—4 in Figure 1.

Figure 5 is a transverse sectional view through the dispersing device as taken on the line 5—5 in Figure 2.

Figure 6 is an enlarged fragmentary view of Figure 4 showing a substance of paste consistency being passed through the device.

Figure 7 is a cross sectional view as taken on the line 7—7 in Figure 1.

Like numerals of reference indicate corresponding parts in the various figures.

Referring to the drawings, the dispersing device consists of a frame as indicated by the numeral 10 and which is of a U-shaped formation. The bottom portion 11 of this frame 10 is adapted to be mounted or rest on any suitable supporting surface, and the end portions 12 and 13 extend vertically upward therefrom. The shaft 14 extends between the end portions 12 and 13 and is journaled in the same by means of the ball bearings 15 and 16, respectively.

The shaft has the bores 17 and 18 extending into the same from each end thereof a predetermined distance. A single roll 19 is fixedly secured on the shaft 14 by keys 14^a and has a central hollow portion 20 within the same. Inlet and outlet holes 21 and 22 extend into the side of the shaft 14 towards the inner end of the bores 17 and 18 therein. An inlet pipe 23 extends into the bore 18 in one end of the shaft 14 thus providing a means of feeding a cooling liquid, such as water, into the central hollow portion 20 within the single roll 19. An outlet pipe 24 extends into the bore 17 and accordingly permits an outlet through which the cooling liquid may be drained from within the single roll 19. In this respect, the cooling liquid continuously enters the central hollow portion 20 of the single roll 19 and is drained therefrom thus providing a means of constantly cooling this single roll.

A dispersing belt 25 is adapted to be held taut over an upper portion of the single roll 19 on the outer surface thereof. This dispersing belt 25 may be made of metal, which would be very flexible, or any other suitable non-stretchable material of sufficient strength for the purpose. The dispersing belt holders 26 and 27, are adapted to hold the dispersing belt 25 in proper relation to the single roll 19, and to engage the same therewith at a constant tension.

The rear dispersing belt bar 28 is supported on a pair of guide pins 29 and 30, which are located at each end thereof. These guide pins 29 and 30 are mounted in the brackets 31 and 32, respectively, and the latter are fixedly secured to the end portions 12 and 13 of the frame 10 on the inner side thereof. These brackets are secured to the end portions of the frame 10 at right angles to the axis of the single roll 19 and at the desired "angle of approach" of the dispersing belt 25 with respect to the periphery of the single roll 19. The compression springs 33 and 34 are mounted on the guide pins 29 and 30 between

the bracket 31 and 32 and the rear dispersing belt bar 28.

The forward dispersing belt bar 35 is essentially the same as that of the rear dispersing belt bar 28 with minor exceptions. This forward dispersing belt bar 35 holds the forward end of the dispersing belt 25 securely in position on the periphery of the single roll 19, and simultaneously makes it possible for the tension of the same to be suitably adjusted with respect thereto. In this respect, the forward dispersing belt bar 35 is adapted to be loosened or tightened with respect to the dispersing belt 25 as may be desired, for various operating conditions in the device and also when it becomes necessary to replace the dispersing belt or change the location of the same. In this instance, the dispersing belt 25 may be adjustably secured in the yoke 36 to one position or another on the supporting members or involute quadrants 37 and 38. Furthermore these supporting members 37 and 38 of a formation somewhat similar to involute quadrants have one or more faces and are rigidly mounted upon the inner surface of the end portions 12 and 13 of the frame 10, and permit the yoke 36, which they support, to be mounted by means of the end pins 36^a and secured in various positions therein.

The threaded pins 39 and 40 on which the forward dispersing belt bar 35 is supported provide a means of adjusting the latter. The threaded pins 39 and 40 extend outward through the yoke 36 and the end wheels 41 and 42 are fixedly secured on the end thereof, thus providing a means of adjusting the same which in turn alters the position of the forward dispersing belt bar 35 and accordingly adjusts the tension on the dispersing belt 25.

The hopper 43 which is arcuately shaped is suitably secured to the inner surface of the end portions 12 and 13 of the frame 10 by means of the bracket extensions 31^a and 32^a at the rear thereof and at the front by the brackets 31^b and 32^b, and located a predetermined distance below the lower portion of the single roll 19. An arcuate space 44 is formed between the hopper 43 and the periphery of the single roll 19, thus providing a receptacle or container in which the paste may be carried before the dispersion thereof.

The control vane 45 is located within the hopper 43 and is supported on the shoulder screws 46 and 47, which are located near the base of this hopper. The control vane 45 is arcuately shaped and larger than that of the single roll 19, and is adapted to control the amount of pre-mixed undispersed material 48 contained within the hopper 43 which may enter the dispersion area. In this instance, the undispersed material within the hopper is carried upward by adherence to the single roll 19 and the scooping action of the control vane 45. In this instance, the control vane 45 restricts the quantity of undispersed material that may adhere to the roll thereby permitting a suitable quantity to be carried upward between the roll and the dispersing belt 25. This control vane 45 is pivotally secured at the bottom thereof to each end of the hopper 43 and the upper portion of the same is supported by an adjusting mechanism. This adjusting mechanism consists of a vertical rod 51 which is suitably secured to the upper portion of the control vane 45 and extends upward therefrom. The upper portion of the vertical rod 51 extends through a bracket 52 which is fixedly secured to the end portion 13 of the frame 10. A collar 53 is fixedly secured on the vertical rod 51 and adapted to

accommodate a compression spring 55 between the same and the bracket 52. A hand wheel 54 is adapted to be threaded on the upper portion of the vertical rod 51 so as to raise or lower the latter with respect to the bracket 52. In this instance, the hand wheel 54 may be tightened down on the vertical rod 51 for raising the same and the control vane 45; and simultaneously this hand wheel may be loosened with respect to the vertical rod 51, thus permitting the compression spring to exert a downward pressure on the same, thereby rolling the upper portion of the control vane outward from the periphery of the single roll.

The scraper chute 56 is suitably located at the front of the device and adapted to take off the dispersed material from the periphery of the roller and directs the same into any suitable container. This scraper chute 56 has a pair of end brackets 57 and 58 fixedly secured thereto, and the latter are adapted to be fixedly secured on the longitudinal rod 59. This longitudinal rod 59 is rotatably supported in the journal blocks 60 and 61 which are fixedly mounted on the end portions 12 and 13 of the frame 10. A control arm 62 is fixedly secured to the longitudinal rod 59 and extends downward therefrom. An adjusting means is adapted to engage the lower end of the longitudinal rod 59 so as to tilt the scraper chute to any suitable position with respect to the single roll 19. This adjusting means consists of a screw 63 threaded into a stationary block and a hand wheel 65 is fixedly secured on the end of this screw. The inner end of a screw 63 is adapted to bear on the front edge of the control arm 62 and a compression spring 66 bears against the rear edge of the same. In adjusting the scraper edge 67 of the scraper chute 56 with respect to the periphery of the single roll 19 the screw 63 may be tightened inward or outward to achieve a desired adjustment. In this instance, the tightening inward of the screw 63 tilts the scraper chute 56 so that the scraper edge moves outward from the periphery of the single roll 19, and simultaneously the releasing of this screw 63 permits the compression spring 66 to tilt the scraper chute 56 inward, thus bearing the scraper edge 67 against the periphery of this single roll. The scraper chute 56 extends outward from the single roll 19 and is provided with side flanges leading to a common opening to the front thereof.

The end scrapers 68 and 69 are suitably secured to the ends of the hopper 43 and adapted to take off any material extending over the edges of the single roll 19 during the dispersion thereof and returning the same to the hopper.

In the operation hereof the undispersed material 48 is placed in the hopper 43, and as the single roll 19 rotates, this undispersed material 48 adheres to the periphery of the same and in co-operation with the control vane 45 is suitably scooped up so that a portion of this material is carried upward between the roll and the dispersing belt 25. The material passing between the periphery of the single roll 19 and the dispersing belt 25 is thoroughly dispersed and the finished product is taken off the roll by the scraper edge 67 on the scraper chute 56. Any remaining material from that portion of the roll is carried downward into the hopper 43 and along with additional material is drawn upward to be passed between the single roll and the dispersing belt a second time and eventually carried therefrom by the scraper chute. Any material extending over the ends of the single roll is picked

up by the end scrapers 62 and 69 and returned to the hopper. The dispersion belt may be suitably adjusted as hereinbefore described so as to create a suitable tension between the same and the periphery of the roll depending on the material to be dispersed and the conditions under which the device may be operating.

The premixed undispersed material to be milled is contained in a suitable receptacle outside the device and suitably fed therefrom to the hopper, one end of the mill structure is taken up by the roller drive, the other end being set up for a suitable feeder system, an opening being left in the frame giving access to an opening in the end face of the hopper near the bottom so that the receptacle may be coupled by a pipe to the hopper, and control means could be placed between the hopper and the receptacle.

What I claim is:

1. In a paint and enamel mill, a frame, a shaft journalled in said frame, a single hollow roll fixedly secured on said shaft, said shaft having a concentric hollow portion extending into each end thereof, and an axial hole leading from each of these concentric hollow portions through the wall of said shaft and forming passageways between the concentric hollow portions and the interior of said single hollow roll, stationary inlet and outlet pipes extending into said shaft and being independent of the movement thereof, said stationary inlet and outlet pipes in co-operation with said shaft providing a means of circulating a cooling liquid through said single hollow roll, a belt engaging the circumference of said single hollow roll, a support member adjustably securing one end of said belt and spring means securing the opposite end of said belt for holding the latter taut over a portion of the circumference of said single hollow roll, a scraper means adapted to engage the circumference of said single hollow roll, an adjusting arm fixedly secured to said scraper means and extending downward therefrom, adjusting means engaging the lower end of said adjusting arm for determining the position of said scraper means with respect to the circumference of said single hollow roll, a hopper adapted to accommodate undispersed material, said single hollow roll extending downward into said hopper and introducing the undispersed material therein, an arcuately shaped control vane located in said hopper and extending inward towards the circumferential surface of said single hollow roll as it extends upward with respect thereto, and the undispersed material within said hopper being carried upward by adherence to said single hollow roll, and said control vane restricting the quantity of undispersed material that may be carried between the circumferential surface of said single hollow roll and said belt thereby providing a means of substantially dispersing the same, and end scrapers secured to the ends of said hopper and adapted to pick up material extending over the ends of said single hollow roll so that the same may be returned to said hopper.

2. In a paint and enamel mill, a frame comprising a bottom portion and end portions extending upward therefrom at right angles thereto, roller bearings supported in the end portions of said frame, a shaft rotatably mounted in said bearings, a single hollow roll fixedly supported on said shaft, and said shaft having a bore extending inward from each end thereof providing access to the hollow portion of said single hollow roll, an axial hole extending outward from each of the bores in said shaft, stationary outlet and inlet pipes extending into the bores in said shaft and being independent of the movement of the latter, thereby providing a means of introducing a cooling liquid into said single hollow roll and the draining of the same therefrom, a flexible dispersing belt adjustably secured on each end thereof and adapted to engage a top portion of the periphery of said single roll, a hopper accommodating the bottom of said single hollow roll and coinciding in shape with the same so as to provide an arcuate space therebetween, a control vane pivotally mounted in said hopper and adapted to be adjustable with respect to the periphery of said single roll for limiting the quantity of undispersing material therein which will pass between the periphery of said single hollow roll and said flexible dispersing belt, a scraper chute adapted to engage the periphery of said single roll and being adjustable with respect thereto, and said scraper chute being adapted to take off the dispersed material from the periphery of said single roll, and end scrapers adapted to engage said single roll for returning any undispersed material passing over the edges thereof to said hopper.
